UNITED STATES PATENT OFFICE.

PAUL VAN MOÉ, OF ROUEN, FRANCE.

PERPETUAL CALENDAR.

Application filed December 24, 1924. Serial No. 757,833.

To all whom it may concern:

Be it known that I, PAUL VAN MOÉ, a citizen of the Republic of France, residing at Rouen, France, have invented certain 5 new and useful Improvements in a Perpetual Calendar, of which the following is a specification.

The object of my invention is to provide a calendar mounting of novel design.

10 In order to make my invention more clearly understood I have illustrated, as an example, an embodiment thereof in and by drawings appended hereto and wherein:

Figure 1 is a front view showing the essential parts of my calendar, as stripped of any mounting made of cardboard, wood, metal or other suitable material, as well as from any adornment.

Figure 2 is a cross sectional view thereof 20 showing the sliding week-day pointer.

Figure 3 represents a front view and a vertical sectional view of the index-slip which constitutes an extra and optional date-pointer. The disposition of this slip 25 is illustrated by Figure 1.

Figure 4 represents a combination of the above referred to perpetual calendar with a pad or block of sheets of paper of known pattern.

30 Figure 5 is a vertical sectional view along line A—B of Figure 4.

Figure 6 is a part sectional view, on an enlarged scale, showing the position of the parts of perpetual calendar with relation 35 to the pad.

In all the figures the same reference numerals denote the same parts.

As will be apparent, the perpetual calendar which is the object of my invention 40 is constituted by a single plate or table 1 (Figure 1) whereon are inscribed all the month-dates.

At the upper part of the said table is located in an appropriate manner an end-45 wise slidable pointer 2 to indicate the days of the week, bearing thirteen inscriptions: Monday, Tuesday, Wednesday, Thursday, Friday, Saturday, Sunday, Monday, Tuesday, Wednesday, Thursday, Friday, Saturday. In order to reduce the length of the 50 pointer, I can also show on table 1 (Figure 1), in the two upper left-hand and right-hand end cases, the inscriptions Monday and Saturday. The pointer itself will 55 then have only eleven inscriptions (Fig-

ure 4). The divisions on this pointer agree with those on the date table.

Said pointer being adapted to slide from left to right and from right to left in front of the date table, I am always able to make 60 the first day in a month to occur with the day on which the month begins. The pointer may then be rendered stationary in some suitable manner, the calendar being adjusted for the whole month. In the construction illustrated, the pointer consists of a strip of material which is folded longitudinally upon itself and fitted over the upper edge of the plate or table so as to straddle the same. In case the material of 70 which the strip is constructed is resilient (which is preferred), the folded strip will thus exert a friction grip upon the table which will serve to retain it in adjusted position; but if non-resilient material be 75 used, then some additional clamping means will be provided.

At the upper part of each date case in table 1 (Figure 1), a hole 3 or any other device may be provided so as to permit the 80 attachment of a coloured pointer, or index, for instance an articulated ring, as shown at 4. This index ring, while optional, serves to frame the date, thereby showing the day's exact date. In order to change the date, I 85 have only to put the index on another date in the same manner as one shifts a plug on a telephone board.

The four vacant cases at the right hand bottom portion of table 1 (Figure 1) are 90 adapted to take the month and year indications.

In order to make my method more clearly understood I will give the following examples:

The month of May in the year 1924 beginning on a Thursday, I slide pointer 2 (Figure 1) so that the word Thursday or the letter T will come opposite the date number "1" as shown (Fig. 1); pointer 2 100 engaging the plate or table 1 with considerable friction will retain its adjusted position by means of its grip. This mere shifting of the pointer will adjust the calendar for the whole month of May 1924. Positioning the index slip 4 will show the day's date at a glance.

Being so adjusted, my calendar will show that May the 31st falls on a Saturday. As regards, therefore, the next month, the user 110

knows, instantly that letter S (Sunday) should be positioned opposite June 1st; but if he should forget until, say, the 5th or the 10th day of June to shift the pointer, the present position of the parts will always indicate the adjustment which should be made.

Utilizations of my novel perpetual calendar are numerous.

For instance, as shown by Figures 4, 5 and 6, the pad or block of sheets mounting which is the subject matter of French Patent No. 531,963 dated the 6th day of November, 1920, can be fitted with this calendar. Suitably marked, the clamping plate 1 of the 10 said pad constitutes the table, and the slide or pointer 2, straddling and riding on the upper part of the plate shows the month-dates, the said slide being assumed in this instance to be made of non-resilient material, though it may, of course, be resilient; in either case fixed adjustment of the table and of the pointer is obtained simultaneously by tightening the clamping nuts 5 on the threaded bolts 6 carried by the 20 back member 7 of the pad.

My calendar may thus be used as a wall-calendar or it may be provided with a back panel or member of card-board or wood, the pointer being in such a case constituted by, 30 for instance, a printed card-board or such like strip sliding under resilient guides or holders.

However used the above described calendar is not cumbersome, is simple to operate and easy to read. Embodying a single table only, it permits all the dates in the present month to be found at a glance while pointing out the week's dates and days.

Having now particularly ascertained and 40 described the nature of my said invention as well as the manner in which the same is to be performed, I declare that what I claim is:

1. A perpetual calendar, comprising a flat

plate whereon the days of the month are 45 indicated in the form of a table having week divisions; and a horizontal indicator strip of sheet material folded longitudinally upon itself and fitted over the upper edge of said plate so as to straddle said edge and 50 slide endwise on the same in either direction, and bearing indicia on the face of its front member representing the days of the week for cooperation with the week divisions of the table; said indicator strip 55 adapted to be held in adjusted position on said plate edge.

2. A perpetual calendar, comprising a flat plate whereon the days of the month are indicated in the form of a table having week 60 divisions; and a horizontal indicator strip of sheet material folded longitudinally upon itself and fitted over the upper edge of said plate so as to straddle said edge and slide 65 endwise on the same in either direction and bearing indicia on the face of its front member representing the days of the week for cooperation with the week divisions of the table; one member of the indicator strip being caused to press against said plate so as to hold the strip in adjusted position.

3. A perpetual calendar, comprising a flat plate whereon the days of the month are indicated in the form of a table having week 75 divisions; and a horizontal indicator strip of resilient sheet material folded longitudinally upon itself and fitted over the upper edge of said plate so as to straddle and frictionally grip the same; said strip being movable endwise in either direction along said plate edge and being held in adjusted position by its friction grip thereon, the front member of the strip bearing indicia on its face representing the days of the week for coaction with the week-divisions of the table.

In testimony whereof I affix my signature.

PAUL VAN MOÉ.
